UNITED STATES PATENT OFFICE.

ROY R. WILEY, OF BUFFALO, NEW YORK.

ILLUMINATED SIGN.

1,215,600.

Specification of Letters Patent. Patented Feb. 13, 1917.

Application filed October 15, 1914. Serial No. 866,817.

To all whom it may concern:

Be it known that I, Roy R. Wiley, a citizen of the United States, residing at Buffalo, in the county of Erie and State of New York, have invented a new and useful Illuminated Sign, of which the following is a specification.

This invention has reference to improvements in illuminated signs, and its object is 10 to provide a sign especially adapted to show-windows, but not necessarily confined to such use, wherein the letters of the sign may be brilliantly illuminated by artificial light from a source invisible to the observer, and 15 whereby the letters are also brilliantly illuminated by daylight.

The present invention comprises a letter holding means upon which suitable letters or other sign characters may be secured, associated with a light source or sources so arranged in conjunction with reflecting means that the letters receive the rays of light at such angles as to appear brilliantly illuminated from a comparatively wide 20 range of angles of observation, the light source, whether single or multiple, being hidden from direct observation and only apparent by the illumination of the letters. The reflecting means associated with the 25 light source is so arranged that certain parts are utilized for daylight illumination of the letters, such utilized reflecting surfaces being invisible to the observer, but directing rays of daylight against the visible surfaces 30 of the letters in a manner to brilliantly illuminate them.

To enhance the effect the letters making up the sign may be made of material having mirror-like characteristics and since the device is intended particularly for show-windows and the like, the carrier for the letters of the sign is made of skeleton type to cause illumination of the window by light rays passing through the carrier and not inter- 40 cepted either by the carrier or the letters.

The illuminated sign may be used in a great variety of different locations and under some circumstances may be inverted; that is, with the letter carrier below instead 45 of above the housing for the light-giving means. The letter carrier is therefore so mounted as to tilt on an axis substantially perpendicular to the line of vision and to the general line of light from the light

source to the letters and then to the eye of the observer, whereby the letters may be readily placed at the most efficient angle to cause the illumination thereof.

The invention is susceptible of use in connection with overhead signs or with double signs, in which latter case the sign may be read by persons traveling in opposite directions.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—

Figure 1 is a perspective view of one form of sign constructed in accordance with the present invention and designed more particularly for use in a show-window.

Fig. 2 is a plan view of the structure shown in Fig. 1.

Fig. 3 is a vertical cross section of the sign of Fig. 1.

Fig. 4 is a vertical cross section of an overhead double sign.

Fig. 5 is a perspective view of another form of the invention, which form is the preferred form.

Fig. 6 is a cross-section of the structure of Fig. 5 similar to the cross-section of Fig. 3.

Fig. 7 is a rear view of a portion of a sign made up of a plurality of structures such as shown in Fig. 5.

Fig. 8 is a section similar to Fig. 6 but omitting parts of the structure, the section being designed to show one manner of mounting the structure.

Fig. 9 is an end elevation showing one manner of supporting the sign in the inverted position.

Fig. 10 is a fragmentary section on the line 10—10 of Fig. 7 and drawn on a larger scale.

Fig. 11 is a view similar to Fig. 10 but showing another manner of fastening a plurality of sign structures together end to end.

Referring to Figs. 1, 2 and 3 there is shown an elongated casing 1 having a portion 2 which may be termed the front portion because presented toward the observer. This front portion is for a considerable part of its height, say, from the lower edge 3 to a point about at 4, of a general curve which may be approximately parabolic, although such particular curvature is not obligatory since other shapes will answer for some purposes. This general shape may be brought about by a series of narrow flat portions 5, or the general curve may be continuous as will appear from other figures to be described. At the upper edge the front portion 2 merges into a top 6 directed toward the rear of the casing for an appropriate distance. The end members of the casing are made as high as the front portion 2, while the rear wall 7 of the casing may be of less height, and near the rear portions of the side walls they are formed with upright extensions 8. The casing is provided with a bottom member 9 and with an intermediate wall made up of a section 10 rising at an angle from the point 3 of the front 2 and then joining a substantially horizontal portion 11 continued toward the rear wall 7 and finally merging into an inclined portion 12 ultimately joining the upper edge of the back 7. The terms of position employed are to be understood as having reference to the installed device in the upright position, for, as will hereinafter appear, the device is susceptible of use to advantage in the inverted position. The inner walls of the front 2, especially between the points 3 and 4, and the upper surfaces of the sections 11 and 12 of the intermediate wall within the casing, are of light reflecting material, preferably polished metal, say, sheet metal, either plain or plated with nickel or with other metals and polished.

The casing below the walls 10, 11 and 12 incloses a chamber 13 designed to contain receptacles 14, 15, the receptacles 14 opening through the wall section 10 adjacent to and toward the front 2, the receptacles 14 being designed to receive incandescent electric lamps 16, and the receptacle 15 being designed to receive an attachment plug for connecting the sign up to a source of electric current, such as the ordinary lighting system of the store or other place where the sign is employed.

The upright extensions 8 are designed to receive an elongated skeleton holder or support 17 for the reception of letters 18 making up the sign, and it is to be understood that the word "letters" is here used as not only meaning alphabetical characters, but sign characters of any kind. The support 17 is made up of a series of longitudinal strips 19 suitably spaced apart and joined at the ends by end plates 19^a, each of which

has about midway of its length a stud 20 projecting therefrom, which stud is extended through the corresponding upright 8 and has a thumb nut 21 threaded thereupon, the studs 20 serving as pintles upon which the sign carrier may be rocked and the thumb nuts serving as locking means for holding the sign in adjusted positions. It will be understood, of course, that any appropriate means for this purpose other than thumb nuts may be employed.

Each strip 19 is made of two parts clamping between them a doubled band 22 so arranged that the doubled portion projects into the space between a strip 19 and the next adjacent strip 19. Ordinarily the carrier includes but four strips 19 arranged in two pairs with the strips of each pair spaced apart and the doubled over portions of the bands 22 entering the spaces between the members of the respective pairs, and these pairs are arranged on opposite sides of the longitudinal center line or axis of the carrier. The bands 22 may be made of felt or other suitable material, and it is customary to cover what may be termed the front faces of the strips 19 with felt, as shown at 23.

The letters 18 have secured to them headed members 24 adapted to enter the spaces between the respective members of the pairs of strips 19, the folded-over portions of the bands 22 entering such spaces yielding to the insertion of the headed members 24 and locking behind them, thus holding the letters to the carrier in a manner preventing their accidental displacement, but at the same time permitting the ready adjustment or removal and replacing of letters. The means of attaching the letters to the sign may be quite different from those shown, and hence the invention is not at all limited in this particular.

The letters 18 may be made of any suitable material capable of prominence under illumination, and as the purpose of a sign is to attract attention it is advisable to make the letters of some material particularly brilliant under illumination. It has been found by experience that a glass letter with a corrugated visible surface and with the rear face silvered becomes particularly brilliant and attractive under illumination and is susceptible of illumination not only by artificial light, but by daylight.

In order that the letters be well illuminated sufficient light must be provided, especially in the case of artificial light, and it is advisable to subdivide the artificial light and thus extend the light-giving source, made up of a series of units, lengthwise of the sign, so that there may be a comparatively even illumination throughout the length of the sign, although there are greatly elongated forms of incandescent lamps which may be employed in place of

multi-sub-division of the source of illumination, and it will therefore be understood that the present invention is not limited to any particular type of arrangement of the light giving source or sources, and that under the term "light-giving source" it is to be understood that any suitable arrangement of light-giving means may be employed.

With a structure such as described the portion 3-4 of the reflector is parabolic, or substantially so, and is depended upon for the main illumination. Let it be assumed that light from the lamp 16 reaches the parabolic part of the reflecting surface and is reflected therefrom along the line 25 to the reflecting surface of the letter 18 and from thence the light is reflected along the line 25^a to the eye of the observer. If the observer is so located as to be at a somewhat different angle to the letter 18 a ray of light from the lamp 16 may follow the line 26 to the reflecting surface 12, and thence on reflection follow the line 26^a to the letter and be reflected therefrom along the line 26^b to the eye of the observer, especially if the observer has approached the sign more closely than before and looks down thereupon at a greater angle. From the usual position of observation the illumination of the letter is due both to the direct light from the lamp and to the light directed upon the letter by the parabolic reflector, the latter contributing very markedly to the even illumination of the letter and preventing bright spots appearing to the detriment of the effect.

Experience has shown that with a device such as illustrated in Figs. 1, 2 and 3 and located in a show-window daylight will not directly illuminate the letters because the letter carrier is tipped forwardly in order to be illuminated by the source of artificial light. However, daylight enters the window from a high point along a line which may be considered as the line 27 and striking the reflecting surface 11 is directed to the letter along the line 27^a, leaving the letter by the line 27^b and ultimately reaching the eye of the observer. Of course, the course of light reaching the letter and being reflected therefrom varies throughout a considerable range, wherefore an observer may be close to or at quite a distance from the sign and still see it well illuminated by daylight because of the reflection from the reflecting surface 11, which is extensive enough to cause light to reach practically the entire surface of the letter at such an angle that despite the forward tipping of the sign it appears to be well illuminated by daylight.

A different adaptation of the principal features of the structure of Figs. 1, 2 and 3 is shown in Fig. 4 where there is illustrated 65 a casing 28 substantially alike on opposite

sides of a central upright line, the casing being hung by means of a chain 30 or otherwise from a suitable support. Each side of the casing, which may be considered as being as long as necessary to accommodate the sign or signs, has near the upper end a parabolic section 31 with an outwardly declined or flaring extension 32 at the lower end merging into a still lower portion 33 also outwardly flaring from above downwardly and finally ending in an inturned depending portion 34, the casing below the lower margins of the side portions 34 being in the main freely open. Extending lengthwise of the casing at a point somewhat above the lower open end is a hollow support 35 which may be conveniently made of sheet metal with the opposite faces 36 converging downwardly for a purpose to be described. Mounted on the support 35 are sockets 37, 85 of which but one is shown, and each socket is designed to receive an incandescent electric lamp 38, the arrangement being such that the lamps 38 are in operative relation to the surfaces of the parabolic reflectors 31, 90 it being understood that the inner surfaces of the parts 32, 33 and 34 and the outer surfaces of the parts 36 are all constructed to readily reflect light. One end of the support 35 may receive a receptacle 39 for an attachment plug.

The casing 28 has end walls 40 closing in the ends of the casing and each end wall has a depending extension 41 of suitable breadth and depth and extending between the depending portions 41 of the end walls is an upright web 42 connecting to the bottom of the support 35 midway of its breadth. Pivoted to the depending portions 41 of the end walls on opposite sides of the web 42 are carriers 43 for sign letters 44, these carriers having pivot supports 45 upon which they may rock and which may be secured in adjusted positions in like manner to the arrangement shown in Fig. 1.

In order that direct rays of light from the lamps 38 may not pass through the open bottom of the casing, shields 46, 47 are provided and are so located as to be in non-interfering relation with the light issuing from the lamps toward the reflecting surfaces or from the parabolic reflectors 31 to reflecting surfaces directing the light to the sign characters. Since it is necessary to have access to the lamps, one of the parabolic reflecting members 31 may be hinged to the casing, as indicated at 48, and provided at a point remote from the hinge with a fastening means 49.

The structure of Fig. 4 is to be supported at such a height that the signs represented by the letters 44 are customarily higher than the eye of the observer or on a level therewith, but in any event the sign will appear to be brilliantly illuminated by artificial

light within the range of angles of observation which may be permitted. Suppose light from the lamp 38 reaches one of the parabolic reflectors 31, which may be assumed to be reflected therefrom along the line 50 to the reflecting surface 33, and from thence passes along the line 50^a to the reflecting surface of the sign on the other side of the upright center line of the casing from the reflector 31, and from thence will pass along the line 50^b to the eye of the observer, this line approaching the horizontal if it be assumed that the observer is at a considerable distance from the sign, the latter being tilted so that its face is directed upwardly to a slight extent. Suppose, however, that the observer is closer to the sign, then it may be assumed that light passes from the lamp 38 along the line 51 to the reflecting surface 32 and from thence along the line 51^a to the reflecting surface 34 and from thence by the line 51^b to the reflecting surface 36, passing from such reflecting surface 36 by the line 51^c to the sign letter 44 and thence by way of the line 51^d to the eye of the observer, the course of the light ray being that caught by the eye of the observer when nearly underneath the casing 28. When not quite so near the sign the course of the light may be by the line 52 to the reflecting surface 33, hence by the line 52^a to the reflecting surface 36, thence by the line 52^b to the sign letter and by way of the line 52^c to the eye of the observer. So long as the observer is at some distance from the casing 28 direct rays from the lamp are obstructed by the casing, but should the observer stand beneath the casing 28 and look up thereinto along, say, the line 53, the shield 46 or 47, as the case may be, cuts off direct rays emitted by the lamp 38 and, moreover, the direct rays of the lamp cannot reach the pavement or other support beneath the sign structure to produce unpleasant glares of light. The shields 46 and 47 also aid in cutting off light rays which by reflection might reach the reflecting surface 36 in a direction to pass out on the open bottom of the casing without striking the sign character. By a suitable adjustment of the signs 44 of Fig. 4 they appear brilliantly illuminated by artificial light and since there are signs on opposite sides of the center line of the casing, observers may see these signs when approaching the casing from opposite sides. The presence of the web 42 prevents the passage of light through one sign to the other, which passage might serve to confuse the observation.

The structures of Figs. 1, 2, 3 and 4 have certain advantages in use, but the structures about to be described with reference to Figs. 5 to 10 have certain advantages over the structures already described, although embodying the same general principles. The structures of Figs. 5 to 10 are therefore pre-

ferred structures because in some features such structures are superior to the first-named structures.

In Fig. 5 and associated figures there is shown an elongated casing 54 with a curved front 55 exteriorly convex and interiorly concave. The front 55 is continued along what may be termed the lower edge for a distance toward the rear and then rises to form an upright wall 56 shown in Fig. 6 as slanting slightly to the rear. This wall rises for but a portion of the height of the casing 54 and then is continued in the form of a rearwardly inclined wall 57 having a greater angle to the vertical than the wall 56. 80

In underriding relation to a portion of the front part of the casing is a bottom wall 58 with an upright extension 59 at the rear ultimately meeting the upper end of the wall 57 which at its upper edge has an angle 85 extension 60 forming an obtuse angle with the wall 57 and finally turned over the upper end of the back wall 59 of the casing as shown at 61, whereby the wall 57 is united to the upper end of the rear wall 59 in any 90 suitable manner, as by solder or otherwise. These various parts are made of sheet metal and in the particular structure shown two pieces of sheet metal are bent into appropriate shape while the upper edge of the 95 front curved wall 55 is turned on itself as shown at 62 to stiffen this part of the structure and to avoid the exposure of any sharp edges.

The casing 54 is provided with end members 63 secured to the walls of the casing 100 in any suitable manner, as by solder, tongues or otherwise.

There are therefore provided two compartments 64 and 65, the latter being practically completely closed by the walls 56 to 60. The wall 56 is considerably below the top of the casing which is open from the front upper edge 62 to the top of the rear wall of the casing, the latter being somewhat lower than the level of the top of the casing, and the ends 63 of the casing being formed at the rear edge with low ears 66 for a purpose to be described.

The wall 56 carries a suitable number of 115 sockets 67 within the compartment 65, but the receiving ends of these sockets project through the wall 56 into the compartment 64 where they may carry electric lamps 68 preferably, though not necessarily of the 120 prevailing high efficiency tungsten type.

The lamp sockets 67 are connected together as usual by conductors 69 leading to a plug receptacle 70 fast to the rear wall 59 preferably near one end thereof, so as to receive a plug 71 at the end of conductors 72 either arranged for connection in the ordinary lighting circuits, or in a manner to be hereinafter described.

On the inner wall of each end 63 there is 130

mounted a slide 73 which may be in the form of an elongated flat narrow metal strip with a longitudinal slot 74 formed therein, and this slot is traversed by bolts 75 extending through the corresponding end walls 63.

5 The slide is continued through the wall 57 above the level of the lamps 68 and also through the rear wall 59 where it may be turned at an angle as shown at 76, and there provided with an entering recess 77, where-

10 by the extension 76 may be hung upon a nail, stud or hook 78 or other suitable support projecting from a wall 79 or other fixture permitting the upholding of the casing 54 on an approximate level and at any distance

15 from the fixture 79 permitted by the longitudinal movement of the slide 73 due to the length of the slot 74, the bolts 75 serving to anchor this slide in any desired position of adjustment.

20 It is sometimes desirable to connect two or more of the casings in line one with the other, especially where an elongation of the sign greater than the length of a unit is desired. Under these circumstances the exten-

25 sions 76 of the slides at the adjacent ends of two sign units are connected together by a strap 80 and bolts 81, so that two or more of the sign units act as a single sign. Such an arrangement is shown in Figs. 7 and 10 and

30 in this case plugs 71^a with a short connecting conductor 72^a complete the electric circuit between the adjoining ends of the sign units. Instead of fastening the casings together in line as shown in Figs. 7 and 10,

35 one slide 73 and the bolts 75 may be removed and other bolts 75^a be used to fasten the meeting ends of the casings together, as shown in Fig. 11.

40 At appropriate points the end members 63 of the casing 54 are perforated near the lower edge at suitably spaced points, as indicated at 82, and matching perforations 82^a are provided in the bottom portions of the casing, so that the ends of chains 83 or 45 other carrying means may be made fast thereto at opposite ends of the casing, whereby the casing may be suspended from some higher support, while in the inverted position as indicated in Fig. 9.

50 For the purpose of carrying the letters or other characters 18 making up the sign, the structure of Fig. 5 and associated figures is provided with a skeleton letter carrier 84

55 which may be readily stamped out of one piece of sheet metal with longitudinal slots 85 having the margins turned rearwardly in the form of longitudinal flanges 86. The ends of the carrier beyond the ends of the

60 slots 85 are formed with flanges 87 turned rearwardly from the face of the carrier until substantially perpendicular to the plane thereof. One extremity 88 of each flange 87 projects beyond the corresponding edge of

65 the carrier, and is turned down over the

flange 86 toward the other end of the carrier. The other end 89 of each flange 87 is more prolonged than the extension 88 and is perforated to form an ear through which there is extended a bolt or pivot pin 90 also traversing the corresponding eye 66.

70 The bolt or pin 90 carries a spring 91 tending to produce a certain amount of friction between the eyes 66 and 89, so that there is a pivot or hinge joint for the letter carrier which will yield to movements of the carrier thereabout, but there is sufficient friction produced to hold the carrier in any position of adjustment against accidental displacement under ordinary conditions of use.

75 The present invention is not directed to the particular construction of the hinge joint, and it is not deemed necessary to describe it in detail, since this hinge joint is both shown and described in detail in a companion application Serial No. 866,818 filed by me on even date herewith wherein claims are made to the construction of the carrier, the letters, and the means for attaching the letters to the carrier both as described with reference to Figs. 1 to 4 and to be described with reference to the remaining figures of the drawing.

80 The hinge or pivot connections 90 permit 95 the rocking of the carrier 84 about an axis slightly below the top of the casing 54 and located near the rear of the casing.

85 In order to serve as a guide for the tipping of the carrier on its pivot supports, both or either ear 89 is formed or provided with a pointer 92, while the inner face of the corresponding end wall 63 has indicia 93 thereon in coactive relation to the pointer 92.

90 While certain letter carrying clips have 105 been described with reference to preceding figures of the drawing, a preferred form of clip is shown in Fig. 6 at 94, this clip being especially adapted to hold the letters 18 in adjusted positions in the carrier 84, but is 110 neither shown in detail nor described herein since these clips are both shown, described and claimed in the aforesaid companion application.

95 Since the carrier 84 may be of considerable length, it is provided either midway of its length or more frequently with a connecting and bracing cross strip 95.

100 The exterior of the casing 54 may be finished in any suitable manner to be unobtrusive, especially at night, while the interior of the casing, and especially the inner surface of the wall 55 and those surfaces of the walls 56, 57 and 60 presented toward the compartment 64 are finished so as to provide reflecting surfaces, these surfaces being nickel plated, or made of aluminum or otherwise produced, and preferably highly polished, so that light striking them is in most 115 part reflected therefrom.

The inner surface of the wall 55 may be of parabolic curvature in cross-section or it may be otherwise formed, since a parabolic form is not absolutely essential, although 5 advantageous. The purpose of the reflecting surfaces is to direct light emitted by the lamps 68 against the visible surfaces of the letters 18, and hence the reflecting surfaces are shaped with this end in view. Moreover, 10 the surface 57 while invisible to the eye of the observer, being hid by the wall 55, is arranged at an angle to direct against the letters daylight reaching it from a high point, whereby the letters become brilliantly illuminated by daylight, as well as by artificial 15 light. The surface 57 contributes to the illumination of the letters and aids in preventing the formation of bright spots which might occur on the highly reflective surfaces of the letters if illuminated from concentrated sources of light. With the reflecting surfaces, however, the light is diffused sufficiently to quite evenly illuminate the 20 whole surfaces of the letters as seen through 25 the front glass of a show-window in which the sign is installed.

In both the single and double sign structures the light sources are shielded from direct observation and the reflectors cause an 30 illumination of the sign characters over substantially their whole surfaces to a sensibly even degree. Since the letter carriers of the different forms of sign shown are pivoted the letters may be tilted to a greater or less 35 degree to thereby attain the best position for the production of the desired result.

In Fig. 1 and associated figures the sign carrier may after adjustment be fixed in such adjusted positions by tightening the 40 thumb nuts 21. In Fig. 5 and associated figures this is unnecessary, since the frictional hold of the pivot supports of the carrier is sufficient to maintain the carrier in adjusted positions. The result is that after 45 the best position is attained the liability of displacement of the letters with relation to the sources of light is reduced to a negligible minimum.

In the structure of Figs. 1, 2 and 3 the 50 overhang 6 shields the sources of light from direct observation in the installed position of the structure, and this same result is brought about in the structure of Fig. 4 by the shields 46 and 47. In Fig. 5 and associated figures the upper portion of the front wall 55 slants rearwardly to such an extent and to such a height that while offering no impediment to clear vision of the sign characters the observer cannot at any time see 55 either the sources of light or the reflecting surfaces. The upper rearwardly inclined portion of the front of the casing therefore, like the part 6 of the structure of Fig. 1 and associated figures, serves as a shield between 60 the light source and reflectors within the 65

casing and the eyes of the observer viewing the sign characters.

The reflecting surface of the rear face of the front wall of the casing whether of parabolic curvature or not, or whether made 70 up of a series of elongated narrow flat portions as in Fig. 1 and associated figures, constitute a reflector which may be generally described as a concave reflector tending to concentrate the light reflected from it in a 75 long and relatively narrow band of sufficient width to quite evenly illuminate letters or other sign characters of the height employed.

What is claimed is:

1. An illuminated sign comprising an elongated opaque casing containing elongated reflecting means and elongated light-giving means associated with the reflecting means, said casing having an open face 85 through which light from the light-giving means is directed by the reflecting means associated therewith, and an elongated carrier for sign characters mounted on the casing on the side thereof remote from the light-giving means and related to the open face of the casing to receive light emitted through the open face of the casing, said carrier being mounted to tilt toward said open face upon an axis disposed lengthwise 90 of the casing whereby light from the casing may be caused to strike reflecting sign characters on the carrier at angles to reach the eye of an observer while the light-giving elements and reflectors are hidden by the 95 casing from the eye of the observer.

2. An illuminated sign comprising an opaque casing with one face open, light-giving means and reflectors within the casing for reflecting light through the open face of 105 the casing, and a carrier with sign characters mounted thereon and provided with reflecting faces, said carrier being mounted on the casing to receive light directed through the open face of the casing and tiltable in a 110 direction toward the light-giving elements and reflectors within the casing to cause the reflecting surfaces of the sign characters on the carrier to direct the light reaching them toward the eye of an observer positioned to 115 have the opaque portion of the casing completely hide the light-giving means and reflectors from view.

3. An illuminated sign comprising an elongated opaque casing with one long face 120 open to emit light therethrough, illuminating means and reflectors corresponding in length to the casing and contained within the latter to be hidden from view by the casing and to direct light through the open 125 face of the casing, and an elongated carrier with sign characters thereon provided with light reflecting faces, said carrier being mounted on the casing exterior thereto and extending along that side of the open face 130

- of the casing remote from the observed side of the casing and tilttable toward the said open face of the casing, whereby light directed through the open face of the casing and striking the sign characters may be reflected from the latter toward the eye of an observer shielded by the opaque portion of the casing from view of the light-giving means and reflectors within the casing.
4. An illuminated sign comprising an opaque casing as long as the sign and provided with internal reflecting means and light producing means associated therewith and both extended in the direction of the length of the casing, said casing having one long face open for the emission of light therethrough, and an elongated carrier mounted on the casing exterior thereto at the side of the open face remote from the light-giving means, said carrier having sign characters thereon provided with mirror surfaces, and said carrier being tilttable toward the open face of the casing to direct light emitted from the casing and striking the mirror faces of the sign characters toward the eye of an observer from whom the light-giving and reflecting means are hidden by the opaque wall of the casing toward said observer.
5. An illuminated sign comprising an elongated casing having the side toward the observer opaque and with the top face open, light-giving means within the casing adjacent to the opaque face, reflectors on the side of the light-giving means toward the opaque face and positioned to direct light through the open face toward the side of the casing remote from the opaque face, and a carrier with sign characters thereon located exterior to the casing and mounted on that side of the casing remote from the reflectors, said carrier being tilttable toward the open face of the casing to cause light reaching the characters from the light-giving elements and the reflectors to be directed toward the eye of an observer on the opaque side of the casing with said opaque side hiding the light giving elements and reflectors from the eye of the observer.
6. An illuminated sign comprising an elongated casing having the side toward the observer opaque and with the top face open, light-giving means within the casing adjacent to the opaque face, reflectors on the side of the light giving means toward the opaque face and positioned to direct light through the open face toward the side of the casing remote from the opaque face, and a carrier with sign characters thereon located exterior to the casing and mounted on that side of the casing remote from the reflectors, said carrier being tilttable toward the open face of the casing to cause light reaching the characters from the light giving elements and the reflectors to be directed
- toward the eye of an observer on the opaque side of the casing with said opaque side hiding the light giving elements and reflectors from the eye of the observer, said casing also containing other reflecting means located nearer to the carrier than the first-named reflecting means and positioned to reflect light entering the open face of the casing from a high point against the reflecting faces of the sign characters upon the carrier, whereby the sign characters are illuminated either by artificial light from within the casing or daylight entering the casing and reflected against the sign characters.
7. An illuminated sign comprising a casing as long as the sign and provided with internal reflecting means also as long as the sign and including both concave and plane reflectors, light-giving means within the casing adjacent to the concave reflector and extended in the direction of the length of the sign, a tilttable carrier supported by the casing on the side of the light-giving means remote from the concave reflector, and sign characters having mirror surfaces and mounted on the tilttable carrier.
8. An illuminated sign comprising a casing as long as the sign and provided with internal reflecting means also as long as the sign and including both concave and plane reflectors, light-giving means within the casing adjacent to the concave reflector and extended in the direction of the length of the sign, a tilttable carrier supported by the casing on the side of the light-giving means remote from the curved reflector, and sign characters having mirror surfaces and mounted on the tilttable carrier, the casing on the side provided with the concave reflector having a portion constituting a shield interposed between the interior of the casing and the eye of the observer of the sign characters.
9. An illuminated sign comprising an elongated casing having internal concave and plane reflecting surfaces, light-producing means within the casing in operative relation to the concave reflecting surface, a tilttable carrier mounted on the casing at the side thereof remote from that side having the concave reflecting surfaces, and sign characters mounted on the tilttable carrier and provided with mirror reflecting surfaces.
10. An illuminated sign comprising an elongated casing having internal concave and plane reflecting surfaces, light-producing means within the casing in operative relation to the concave reflecting surface, a tilttable carrier mounted on the casing at the side thereof remote from that side carrying the concave reflecting surfaces, and sign characters mounted on the tilttable carrier and provided with mirror reflecting surfaces.

faces, the casing and carrier being provided with coacting means at the axis of tilting for holding the carrier in adjusted positions.

11. An illuminated sign comprising a tilt-
5 able carrier, sign characters thereon having reflecting surfaces, light-producing means in operative relation to the sign characters, and a casing inclosing the light-giving means said casing being provided with a concave reflector in operative relation to and in front of the light-producing means to direct rays of light against the reflecting surfaces of the sign characters, and said casing having another reflecting surface in operative relation to the sign characters and on the side of the light-giving means remote from the concave reflector.

12. An illuminated sign comprising a tilt-
20 able carrier, sign characters thereon having reflecting surfaces, light-producing means in operative relation to the sign characters, and a casing inclosing the light-giving means, said casing being provided with a concave reflector in operative relation to and in front of the light-producing means to direct rays of light against the reflecting surfaces of the sign characters, and said casing having another reflecting surface in operative relation to the sign characters and on the side of the light-giving means remote from the concave reflector, the casing being also provided at the front with a shield interposing between the light-giving means and the reflecting surfaces and the eye of an observer
35 viewing the sign characters.

13. An illuminated sign comprising a casing having an interior concave reflecting surface at the front portion of the casing, light-giving means within the casing adjacent to the reflecting surface, a carrier mounted on the casing at the rear side thereof, and sign characters with reflecting surfaces mounted on the carrier, the casing also containing a plane reflecting surface nearer to the carrier than are the light-giving means and concave reflecting surface, and positioned to receive rays of light from outside of the casing and direct such rays of light on to the sign characters at angles as
45 to cause the light to be reflected toward the observer.

14. An illuminated sign comprising a casing with the inner wall at the front concavely curved and at the top shaped to constitute a shield hiding more remote parts of the interior of the casing from view, said concave wall having its surface constituting a reflector for light, a wall rising from the bottom of the casing in spaced relation to both the front and back of the casing and from thence continuing as a plane reflecting surface to the back of the casing, light-giving means mounted on the intermediate wall between the latter and the concave reflecting surface and located in the lower por-

tion of the casing, a tilttable carrier mounted on and rising from the rear portion of the casing, and sign characters mounted on the carrier and provided with reflecting surfaces directed toward the front of the casing and the reflectors within the casing.

15. An illuminated sign comprising a casing with the inner wall of the front concavely curved and at the top shaped to constitute a shield hiding more remote parts of the interior of the casing from view, said concave wall having its surface constituting a reflector for light, a wall rising from the bottom of the casing in spaced relation to both the front and back of the casing and from thence continuing as a plane reflecting surface to the back of the casing, light-giving means mounted on the intermediate wall between the latter and the concave reflecting surface and located in the lower portion of the casing, a tilttable carrier mounted on and rising from the rear portion of the casing, and sign characters mounted on the carrier and provided with reflecting surfaces directed toward the front of the casing and the reflectors within the casing, said carrier being mounted on the casing in position to receive both direct and reflected light from the light-giving means and for tilting movements on an axis longitudinal of the casing.

16. An illuminated sign comprising a casing with the inner wall at the front concavely curved and at the top shaped to constitute a shield hiding more remote parts of the interior of the casing from view, said concave wall having its surface constituting a reflector for light, a wall rising from the bottom of the casing in spaced relation to both the front and back of the casing and from thence continuing as a plane reflecting surface to the back of the casing, light-giving means mounted on the intermediate wall between the latter and the concave reflecting surface and located in the lower portion of the casing, a tilttable carrier mounted on and rising from the rear portion of the casing, and sign characters mounted on the carrier and provided with reflecting surfaces directed toward the front of the casing and the reflectors within the casing, said carrier being mounted on the casing for tilting movements on an axis longitudinal of the casing, and said carrier and casing having coacting means for holding the carrier in adjusted positions and also with means for indicating the degree of tilting of the carrier.

17. An illuminated sign comprising an elongated opaque casing having an elongated open face, a series of light-giving elements within and extended lengthwise of the casing at one side of the open face and in position to be hidden from view by opaque portions of the casing, elongated reflecting means common to all the light-giv-

- ing elements and located near said light-giving elements and the opaque portion of the casing hiding said elements from view, and a tilttable carrier exterior to the casing and supported by the latter on the side of the open face of the casing remote from the light-giving elements, said tilttable carrier being adapted to receive the sign characters and tilttable to an extent to direct light emitted from the casing through the open face thereof to the eye of an observer shielded by the opaque portion of the casing from direct view of the light-giving elements and the reflecting means within the casing.
18. An illuminated sign comprising a casing with interior reflecting means located at the front thereof, light-giving means within the casing in operative relation to and at the rear of the reflecting means, a carrier supported by the casing at a higher point than and to the rear of the light-giving means, and reflecting sign characters adapted to the carrier, the carrier being of skeleton form to permit the passage of light through it between the sign characters to cause illumination back of the casing and carrier.
19. An illuminated sign comprising a casing having the inner surface of its front wall reflective and concavely curved, light-giving means within the casing in operative relation to the curved reflecting surface, a plane reflecting surface within the casing extending from the light-giving means toward the rear of the casing at a rising angle, and the front and sides of the casing rising to a higher point than the plane reflecting surface to shield the reflecting surfaces and the light-giving means from direct observation, a skeleton carrier mounted on the rear of the casing and projecting above the top of the casing to provide for the passage of light through the carrier toward the rear, and sign characters mounted on the carrier and provided with reflecting surfaces.
20. An illuminated sign comprising a casing having the inner surface of its front wall reflective and concavely curved, light-giving means within the casing in operative relation to the curved reflecting surface, a plane reflecting surface within the casing extending from the light-giving means toward the rear of the casing at a rising angle, and the front and sides of the casing rising to a higher point than the plane reflecting surface to shield the reflecting surfaces and the light-giving means from direct observation, a skeleton carrier mounted on the rear of the casing and projecting above the top of the casing to provide for the passage of light through the carrier toward the rear, and sign characters mounted on the carrier and provided with reflecting surfaces, said skeleton carrier having

pivotal connections at the lower edge with the upper rear portion of the casing and rockable on the pivots into different angular relations to the light-giving means and the reflectors within the casing.

21. An illuminated sign comprising a casing with light-giving means therein, and provided with an opening for the emission of light, and a carrier exterior to the casing and provided with sign characters, the carrier and characters being located with respect to the opening in the casing to be illuminated by light emitted therefrom, said casing being also provided with rearwardly extensible supports closely adjacent to the ends and constituting means for sustaining the casing and for joining a plurality of casings end to end.

22. An illuminated sign, comprising an elongated casing with an elongated light emitting opening and with electric lighting means within the casing in position to direct light through the light emitting opening of said casing, extensible members projecting from the rear of the casing closely adjacent to the ends of the latter, coupling sockets at the ends of the casing electrically coupled up with the electric lighting means within the casing, and an elongated carrier on the casing exterior thereto and provided with sign characters in the path of light directed through the light emitting opening of the casing, whereby two or more of the elongated casings with the carriers mounted thereon may be coupled end to end both mechanically and electrically into a single sign a plurality of times longer than a single casing.

23. An illuminated sign comprising an elongated casing with a correspondingly elongated light emitting opening, elongated reflecting surfaces within the casing, light giving means within the casing extended lengthwise thereof and related to the reflecting surfaces and both the light-giving means and the reflecting surfaces being related to the light emitting opening of the casing to direct light through the opening throughout its length, and an exterior elongated carrier supported by the casing in light receiving relation to the light emitting opening thereof and provided with sign characters having reflecting surfaces, said carrier being tilttable into different relations to the light emitting opening on an axis longitudinal of the carrier, and the carrier and the portion of the casing supporting it having coating means for holding the carrier in the different tilted positions.

24. An illuminated sign comprising an elongated casing with an elongated light emitting opening, said casing being provided with interior reflecting surfaces and interior light giving means both related to each other and to the light emitting opening

of the casing to direct light through said opening, and an exterior tilttable carrier mounted on the casing in light receiving relation to the light emitting opening thereof and provided with sign characters having smooth mirror reflecting surfaces, the carrier and the portion of the casing on which it is mounted having coacting means for holding the carrier in different tilted

10 positions with relation to the casing.

25. An illuminated sign, comprising a casing with a light emitting opening and interior light-giving means related to the opening to direct light therethrough, and
15 an exterior tilttable carrier mounted on the casing in light receiving relation to the light emitting opening thereof and provided with

sign characters having reflecting surfaces, said casing being provided with means on the part thereof remote from the light emitting opening for suspending the casing with the carrier lowermost, and the light-giving means hidden by the casing from the eyes of an observer of the sign characters on the carrier when illuminated by the light-giving means within the casing. 20 25

In testimony that I claim the foregoing as my own, I have hereto affixed my signature in the presence of two witnesses.

ROY R. WILEY.
